UNITED STATES PATENT OFFICE

WILLIAM S. PEARSON, OF WILMETTE, ILLINOIS

LAMP SHADE

Application filed January 8, 1931. Serial No. 507,334.

- The present invention relates to lamp shades generally and has to do more particularly with shades composed of plates arranged as an enclosure for the source of light.
- 5 The invention includes a novel arrangement of the plates which is capable of a great variety of adaptations and uses. In brief, certain plates lie flatwise toward the light while others, grouped in sets, lie edgewise toward the same source. The walls of the shade are made up by combining these flatwise and edgewise elements so as to more or less inclose the source of light, which is usually an electric lamp.
- 10 In the particular embodiment illustrated, wherein the shade is adapted for use as an upright structure mounted upon a flat base, there are other features of novelty than the important one of the flatwise and edgewise arrangement just mentioned. These additional features include the connections of the shade to the base and the positioning of the plates so as to produce not only an attractive device to direct observation but also to an indirect view, such as may be had when the device is on a dressing table before a mirror.
- 15 The various features and advantages of my invention will be more fully understood upon reference to the following detailed description taken in connection with the accompanying drawings wherein a preferred embodiment of the invention is shown. For a measure of the invention reference should be had to the appended claims.
- 20 In said drawings, Fig. 1 is a perspective view of a lamp shade constructed in accordance with the present invention and mounted upon a base adapted to rest upon a table or other like support; Fig. 2 is a front elevation of the device upon a somewhat enlarged scale, a portion of the front plate being broken away; Fig. 3 is a side view of the device illustrating the upper portion in elevation and the lower portion in section, the plane of section being indicated by the line 3—3 of Fig. 2; and Fig. 4 is a central section through the device taken on a plane indicated by the line 4—4 of Fig. 2. Throughout these views like characters refer to like parts.
- 25 Essentially, the invention consists in forming the walls of the shade which partially or completely inclose the lamp or other source of light with two kinds of plates, the one a relatively large plate lying flatwise toward the lamp space, and the other a set of narrow plates spaced apart and lying edgewise toward the lamp space.
- 30 In the embodiment illustrated, there are two relatively large plates designated 10 and 11, and two sets of the narrow plates, the one set being designated 12, 13 and 14, and the other set 15, 16, 17. These plates inclose a central lamp space in which is located an electric lamp 18. In this embodiment there are also two narrow plates 19 and 20 which lie edgewise toward the lamp space and form what may be termed the upper end wall of the shade. As clearly shown, the edgewise plates in this embodiment are spaced from each other and lie in planes which extend in the same general direction as the planes of the large plates 10 and 11. In order to secure the plates together various means may be used. Preferably, however, I use a number of headed pins 22, 23, 24 and 25, each being associated with suitable spacers in the form of sleeves through which the pins are threaded. In the case of pins 22 and 23 these sleeves, designated 26, are practically the same length and space the plates 10, 15, 19, 16, 20, 17, 80 and 11, in the order mentioned. Two spacing sleeves 27 are associated with the pins 24 and 25 and space the plates 15, 16 and 17. The plates 10, 15 on the one hand, and 11 and 17 on the other, are spaced by projecting clips 28 and washer 28^a, the clips also serving in this embodiment to secure the shade to the base 29. The headed pins 22, 23, 24, 25, when in assembled position are provided with heads or nuts 30 by which the several plates are firmly forced into engagement with the spacers and permanently held in such position. In some cases the heads, which are applied after assembly, may be rivet heads, or other means might be employed for accompanying the result mentioned.
- 35 Not only is it possible to combine the elements consisting of the large plates lying flatwise toward the lamp space and the sets of narrow plates lying edgewise toward the
- 100

lamp space, into various forms of inclosing shade walls, but it is obvious that the plates themselves may be variously formed in outline and also variously treated and ornamented. Commonly, these plates are composed of glass. In some instances this glass may be left clear and transparent while in other instances it may be frosted and treated so as to become merely translucent, as illustrated. Again, in other instances the plates may be entirely opaque. This would be true in a decorative scheme where it was desirable to employ only the light passing laterally from the lamp through the spaces between the edgewise plates, such as the plates 12, 13, 14, the plates 15, 16, 17, and the plates 19 and 20. In still other cases certain of the plates might be opaque and others transparent or translucent. It is obvious that a great many different arrangements might be decided upon, in all of which the essentials of the present invention would be present. Likewise in many instances plates of celluloid or other transparent or translucent material might be employed, or where the plates were to be opaque, a great variety of materials might be used for the manufacture of the plates.

In the particular embodiment shown, the upright shade structure is secured to the base 29 by means of the projections 28 which pass down into sockets formed in the upper face of the base 29. The lower ends of the projections 28 are apertured and pins 31 pass through a horizontal bore in the base 29 and through the apertures in the projections 28 and so securely hold the shade to the base.

As clearly shown, the lower portion of the shade in the illustrated embodiment has no cross plates and thus provides a suitable space for the electric lamp socket 32 which is secured in an opening in the upper face of the base by any suitable means. The electrical connections for the lamp socket 32 include the conductors of the lamp cord 33. Preferably the latter is enclosed in a compound forming part of the base and is located as clearly illustrated. The socket 32 is also preferably provided with an electric switch controlled by a pull 34 passing outward between certain of the plates such as the plates 16, 17.

When it is desired to remove the shade from the base it is only necessary to withdraw the pins 31. When this is done the shade may be readily lifted free of the base and the lamp. In case it becomes necessary to change the lamp, this can be done when the shade is removed from the base. When the lamp is restored or replaced by a new lamp, then the shade may be applied to the base by passing the projections 28 down into the sockets and again inserting the pins 31.

Obviously, the base 29 may be constructed with the outer shell 35 and inner filling 36

and a bottom wearing material 37. The latter, if desired, might be a piece of felt or in some cases it might be metal. The filling 36 would ordinarily be an electrical insulating compound and the outer shell 35 preferably metal. This base construction, however, is not a matter of importance and might be changed according to the wishes of the designer or manufacturer of the device.

From what has been said, it will be seen that I consider the invention capable of a great variety of uses and appreciate that the same may be used in forming shades of very many different shapes. Obviously, when different shapes and uses are contemplated, the supports for the shades must be greatly varied. The same would also be true of the arrangements of lamps within the shade. I therefore do not wish to be limited to the embodiment herein disclosed nor to embodiments departing slightly therefrom, but aim to cover a wide range of uses and adaptations of the invention, by the terms of the appended claims, which are drawn with a view to giving an exact measure of the invention.

What I claim as new and desire to secure by a patent of the United States is:

1. A lamp shade including walls composed of plates positioned adjacent to the lamp space and more or less completely enclosing the same, said plates comprising a plurality of relatively large plates forming parts of the wall structure and lying flatwise toward the lamp space and sets of relatively narrow plates forming other parts of the wall structure, certain of said sets being positioned between the side edges and others between the end edges of said large plates, all of said narrow plates lying edgewise toward the lamp space, and means for spacing the plates of each set of narrow plates apart from each other and securing all of said plates, large and narrow, in fixed relation to each other.

2. A lamp shade including walls composed of plates positioned adjacent to the lamp space and more or less completely inclosing the same, said plates comprising two relatively large plates forming parts of the wall structure on opposite sides of the lamp space and lying flatwise toward said space, sets of relatively narrow plates forming those parts of the wall structure between the side edges of said large plates, and other like narrow plates forming the end part of the wall structure between the end edges of said large plates, all of said narrow plates lying edgewise toward the lamp space, and means for spacing said narrow plates apart from each other and from said large plates and securing all of said plates, large and narrow, in fixed relation to each other.

3. A device of the class described comprising a base, a socket in said base for receiving and holding an electric lamp, front and rear lamp shade plates extending upward from

said base and transversely thereof completely over the front and rear of the lamp position to include the same between them, narrow lamp shade plates likewise extending upward from said base at the sides of said socket transversely of said base to about the same height as said front and rear plates, and means for securing all of said plates in spaced relation.

10 4. A device of the class described comprising a base, a socket in said base for receiving and holding an electric lamp, front and rear lamp shade plates extending upward from said base and transversely thereof completely over the front and rear of the lamp position to include the same between them, narrow lamp shade plates likewise extending upward from said base at the sides of said socket transversely of said base to about the same height as said front and rear plates, one or more top lamp shade plates extending transversely across the top of the lamp position at about the height of said front and rear plates, and means for securing all said plates together in spaced relation.

15 5. A device of the class described comprising a base having small sockets extending into the base from the top and bores extending from the outside of the base through said small sockets, an electric lamp socket in said base for holding a lamp on its upper side, lamp shade plates, holding elements extending into said small sockets, retaining pins passing through said bores and openings in said elements for securing said plates to said base, said plates being positioned about the lamp position, and means for securing said plates and holding elements together in proper relation, all said plates extending in the same general direction side by side.

20 6. A device of the class described comprising a base having small sockets opening upward and bores extending through said sockets, an electric lamp socket upon the upper side of said base, large front and rear plates before and behind the lamp position, holding elements extending into said small sockets, retaining pins passing through said bores and openings in said holding elements for securing said front and rear plates to said base, other plates at the sides of said lamp socket extending side by side in the same general direction as said front and rear plates but between them and spaced from them and each other, and means for holding said plates and holding elements in proper relation.

25 7. A device of the class described comprising a base having small sockets opening upward and bores extending through said sockets, an electric lamp socket upon the upper side of said base, large front and rear plates before and behind the lamp position, holding means extending into said small sockets, retaining pins passing through said bores and openings in said holding means for securing

said front and rear plates to said base, narrow side plates of glass likewise extending upward from said base at the sides of said lamp socket in the same general direction as said front and rear plates and to about the same height, similar narrow top plates of glass extending in the same general direction as said front and rear plates near their tops, and means for securing all said plates and said holding means together in proper relation.

30 8. A lamp shade including walls of large outer plates and narrow intervening plates, all of substantially the same length and extending generally in the same direction, said large outer plates extending on opposite sides over the lamp space and including said space between them, said large plates thus lying flatwise to said space, said narrow plates being in sets, and said sets lying between the side edges of said large plates on opposite sides of the lamp space, the narrow plates thus lying edgewise to the lamp space, and means for spacing each set of narrow plates apart from each other and from said large plates and securing all said plates, large and narrow, in fixed relation to each other.
